(57) CLAIM

I claim the ornamental design for a cap, as shown and described.

DESCRIPTION

FIG. 1 is a front perspective view of the cap;
FIG. 2 is a top view of the cap with the front of the cap being at the bottom of the figure;

FIG. 3 is a front view of the cap;

FIG. 4 is a back view of the cap;

FIG. 5 is a right side view of the cap, the left side being a mirror image; and,

FIG. 6 is a bottom view of the cap with the front of the cap being at the bottom of the figure.

The matter shown in dashed lines forms no part of the claimed design.
